(57) **CLAIM**

The ornamental design for a table, as shown and described.

DESCRIPTION

FIG. 1 is a perspective view of a design for a table; FIG. 2 is a side elevational view of the design as seen in FIG. 1, all four side elevational views being identical to FIG. 2; FIG. 3 is a top plan view of the design as seen in FIG. 1; and, FIG. 4 is a bottom plan view of the design as seen in FIG. 1.

The broken lines show portions of the table that form no part of the claimed design.
